(57) CLAIM

The ornamental design for a produce container, as shown and described.

DESCRIPTION

FIG. 1 is a perspective view of a produce container showing our new design; and,

FIG. 2 is a perspective view of another embodiment of FIG. 1. The portions of the article in broken lines are shown for illustrative purposes only and form no part of the claimed design.

1 Claim, 2 Drawing Sheets

FIG. 1

FIG. 2
